CHARLES E. LUCKE, OF NEW YORK, N. Y., ASSIGNOR TO THE BABCOCK & WILCOX COMPANY, OF BAYONNE, NEW JERSEY, A CORPORATION OF NEW JERSEY

SUPERHEATER AND PROCESS OF OPERATING THE SAME

Application filed May 15, 1928. Serial No. 277,824.

This invention relates to a steam boiler that is provided with two superheaters, one of which may be heated by radiant heat from the boiler furnace and the other is heated by contact with hot gases passing over the same. By this invention the steam passing through the respective superheaters is so regulated that the proper degree of superheat can be obtained with variations in the load. The steam from the steam drum of the boiler is caused to pass through the two superheaters in parallel. The most or all of the steam is caused to pass through the radiantly heated superheater at low ratings and larger proportions of the steam are passed through the other superheater at higher ratings.

The invention will be understood from the description in connection with the accompanying drawings in which Fig. 1 is a vertical section through an illustrative embodiment of the invention, and Fig. 2 is a section on an enlarged scale showing details of the regulator. In the drawings reference character 1 indicates the furnace of a boiler above which is illustrated a boiler of the Babcock & Wilcox type having the usual steam and water drum 2, and a bank of inclined tubes 3 connected to uptake headers 4 and downtake headers 5 in the usual way. Baffles 6 direct the hot products of combustion from the furnace 1 a plurality of times over the bank of tubes 3 to the gas outlet 7.

A superheater 8 is located above the bank of tubes 3 in such a position as to be swept over by the gases after they have passed once across the bank of tubes 3. It is to be understood that such a position is often designated "standard," and the word as used herein is intended to have this meaning. Another superheater 9 is located along the inside wall of the furnace in such a position that it will be heated by radiant heat from the furnace. A pipe 10 connects the steam space of the steam and water drum 2 to a two-way valve 11 that is shown in detail in Fig. 2. A pipe 12 leads from one of the outlets of the valve 11 to the superheater 8 from which a pipe 13 leads to the steam outlet pipe or steam main 14. A pipe 15 leads from the other outlet of the valve 11 to the radiant heat superheater 9

from which a connection 15 extends to the steam main 14.

The valve 11 is provided with a regulator comprising an upper cylindrical member 17 with a lower serrated end 18 and a lower cylindrical member 19 provided with an upper serrated end 20. The lower member 19 is closed at the bottom as shown at 21. A rod 22 connects the cylindrical members 17 and 19 by means of spiders 23. The lower end of the valve casing merges into one leg 24 of the U-tube 25 containing a liquid, such as mercury, for example. The other leg 26 of the U-tube is connected by means of the pipe 27 to the steam outlet main 14.

The operation is as follows: The valve 11 operates automatically to divide the steam that passes through the superheaters 8 and 9, respectively, in such a manner that larger proportions of steam pass through the superheater 8 at higher ratings so that the mixed steam from the two superheaters will have the proper amount of superheat at different loads. It is well known that a characteristic of radiant heat superheaters is that they give a falling temperature curve with increasing loads and that a superheater located like the superheater 8 gives a rising temperature curve with increasing loads so that by increasing the proportion of steam that passes through the superheater 8 at increasing loads, the proper amount of superheat can be maintained in the total steam passing from the boiler. It will be understood that the word "characteristic" applied to a superheater defines the nature of change of final temperature with respect to increase of load. The pressure drops through the superheaters between the pipes 10 and 14 are, of course, greater at high loads so that the mercury rises in the leg 26 of the U-tube 25 and that in the leg 24 lowers when the load is increased, thus causing the cylinders 18 and 19 to descend with the result that a larger proportion of the steam is permitted to pass through the outlet and pipe 12 into the superheater 8 and a smaller proportion passes through the outlet and pipe 15 into the superheater 9.

The invention is also applicable to superheaters located at different positions any-

where in the boiler in one of which superheaters there is a rising or constant temperature curve with increasing loads and in the other there is a falling temperature curve with increasing loads, whether either one of said superheaters is radiantly heated or not. When one of the superheaters is radiantly heated then the invention serves to protect it from overheating and burning quite independent of the constancy of steam temperature. In connection with the invention herein disclosed, it is to be noted that subject matter not herein claimed is disclosed and claimed in my copending application Serial No. 575,604, filed November 17, 1931.

15 I claim:

1. The process of regulating the amount of superheat in steam passing from a boiler, which comprises passing a portion of the steam from the boiler through a radiantly heated superheater and another portion through a standard superheater, uniting the steam after it has passed through the superheaters, and controlling the relative amounts 20 of steam that passes through the superheaters by the difference in pressures at the inlets and outlets of said superheaters so that a proportionately larger amount of steam passes through the standard superheater as the total is increased.

30 2. The process of regulating the amount of superheat in steam passing from a boiler, which comprises superheating a part of the steam from the boiler by radiant heat from the boiler furnace and another part by hot gases from the furnace, uniting the parts and controlling the proportions of the two by the difference in pressures at the inlets and outlets of said superheaters so that a proportionately larger amount of steam is heated 35 by hot gases from the furnace as the total is increased.

3. The process of regulating the amount of superheat in steam passing from a boiler, which comprises passing a portion of the steam from the boiler through a radiantly heated superheater and another portion through another superheater, uniting the steam after it has passed through the superheaters, and decreasing the proportionate 45 amount that passes through the radiantly heated superheater when the total is increased.

4. The process of regulating the amount of superheat in steam passing from a boiler, which comprises passing a portion of the steam through a superheater having a rising temperature curve and another portion through another superheater having a falling 55 temperature curve with increasing loads, uniting the steam after it has passed through said superheaters, and controlling the relative amounts of steam that pass through said superheaters by the difference in pressures at the inlets and outlets of said superheaters so

that the proportionate amount of steam that passes through the superheater having a falling temperature curve decreases when the total is increased.

5. The process of regulating the amount of superheat in steam passing from a boiler, which comprises passing a portion of the steam from the boiler through a radiantly heated superheater and another portion through another superheater, uniting the steam after it has passed through the superheaters, and decreasing the proportionate amount that passes through the radiantly heated superheater when the total is increased in such a manner that substantially constant steam temperature is maintained at different loads.

6. The process of regulating the amount of superheat in steam passing from a boiler, which comprises superheating a part of the steam from the boiler by radiant heat from the boiler furnace and another part by hot gases from the furnace, uniting the parts and controlling the proportions of the two by the difference in pressures at the inlets and outlets of said superheaters in such a manner that the metal of the radiantly heated superheater is prevented from being overheated by passing a relatively greater proportion of the steam through it at low loads.

7. In a water tube steam boiler, two superheaters, one of said superheaters comprising a single row of tubes along the boiler furnace and heated mainly by radiant heat, the other one comprising a multiplicity of tubes in parallel mainly screened from radiant heat by tubes of said boiler and receiving heat of gases from said furnace after they have passed over tubes of said boiler, and means connected to the steam outlet to control the proportion of steam that passes through said superheaters, said means simultaneously increasing the amount of steam that passes through one superheater as it decreases the amount that passes through the other one, said means being arranged and adapted to start and stop said increase and decrease together.

8. In a water tube steam boiler, two superheaters, one of said superheaters comprising a single row of tubes along the boiler furnace and heated mainly by radiant heat, the other one comprising a multiplicity of tubes in parallel mainly screened from radiant heat by tubes of said boiler and receiving heat of gases from said furnace after they have passed over tubes of said boiler, and means connected to the steam outlet to control the proportion of steam that passes through said superheaters, said means comprising two mechanically and rigidly connected pressure actuated valves.

9. In a water tube steam boiler, two superheaters, one of said superheaters comprising a single row of tubes along the boiler

furnace and heated mainly by radiant heat, the other one comprising a multiplicity of tubes in parallel mainly screened from radiant heat by tubes of said boiler and receiving
5 heat of gases from said furnace after they have passed over tubes of said boiler, and means connected to the steam outlet to control the proportion of steam that passes through said superheaters, said means comprising two
10 mechanically and rigidly actuated valves actuated by the difference in pressures at the inlet and outlet ends of said superheaters and controlling passage of steam through both superheaters.
